UNITED STATES PATENT OFFICE

2,220,520

HEATER

Robert O. Hein, Chicago, Ill., assignor to Sears, Roebuck and Co., Chicago, Ill., a corporation of New York

Application June 9, 1937, Serial No. 147,290

5 Claims. (Cl. 98—101)

This invention relates to heating and other air conditioning, and is concerned more particularly with an air flow control for hot water and other heaters for the passengers of conveyances, occupants of rooms and in other installations.

An object of my invention is to provide a heating device with manually releasable louvers or blades adapted to be automatically opened to discharge heated or other air.

10 A further object is to provide a heater with an opening whose size is variable.

Another object is to provide a device of the character referred to with doors or louvers adapted to be automatically held open to a predetermined extent.

15 It is also an object of the invention to provide a gang of louvers adapted to open simultaneously and to be individually or simultaneously adjusted and closed.

20 It is another object to provide an air conditioning device for an automobile and readily accessible to the driver and/or a passenger.

Another object resides in the provision of a gang of louvers of such size as to afford adequate 25 volume of air discharge for an enclosure such as an automobile, and adapted to be closed simultaneously or substantially so by a single movement of the hand or foot of an occupant.

25 Further objects and advantages of my invention will appear as the description proceeds.

The invention is illustrated in the accompanying drawing, in which:

Fig. 1 is a horizontal sectional view through a heater embodying my invention, taken as indicated by the line I—I in Fig. 2.

35 Fig. 2 is an enlarged fragmentary vertical sectional view, taken as indicated by the line II—II in Fig. 1.

Fig. 3 is a fragmentary horizontal sectional view showing louvers in various adjustments.

40 Fig. 4 is a fragmentary diagrammatic view showing a Bowden wire release installation for the louvers.

Fig. 5 is a reduced front elevation of the device.

45 Referring now more particularly to the drawing, there is shown a hot water heater such as may be found on vehicles such as automobiles, although it will be understood that a cooling or any other type of air conditioning or ventilating apparatus may be employed since my invention resides primarily in the louver construction and control mechanism therefor.

50 The heating unit comprises in general a frame 11, a motor 12, a suitable switch therefor (not shown), a fan 13, an air inlet 14 and a radiator

15, the connections to which are not shown, but may extend to the engine cooling system. The escape of heated air influenced by the radiator is controlled by louvers 16 in accordance with my invention.

Each louver is hinged at its top and bottom in any suitable manner to the frame and has ears 18 and 19 which receive the hinge pins 20 and 21, respectively. A spring 22, anchored at one end to a stud 23, passes about the adjacent hinge pin 10 20 and has its free end engaged with the inner side 24 of the louver, constantly urging the louver to swing open.

Slidably and non-rotatably mounted within the frame as at 26 and 27 is a plunger rod 28 carrying, in juxtaposition to the inner sides of the closed louvers, as shown in Fig. 1, a spring latch 29 adapted to interlock with a hook or catch 30 mounted on the inner side of each louver. The hook 30 has a cam surface 31 which, upon closing 20 of the louver, springs the free end of the latch and passes therebeyond so that said free end snaps into the recess 32 in the hook and thus positively prevents opening of the louver.

25 A spring 34 about the plunger and engaged between the frame and an abutment 35 on the plunger urges it outward so as to locate the latches in positions to automatically connect with the catches as the louvers are moved to closed positions. An abutment 36 on the plunger is engageable with the frame to prevent the spring 34 from moving the plunger too far.

30 An end of the plunger or rod 28 in accordance with one form of my invention has a button 38 which projects out of the casing or frame 11 at a point preferably where it is readily accessible to the hand of an occupant of the vehicle or other installation place.

35 Pressure on the button overcoming the resistance of the spring 34 will move the latches out of all of the catch recesses 32 simultaneously, as shown in dotted lines in Fig. 3, whereupon the springs 22 automatically swing the louvers open.

40 Upon release of the button 38, the spring 34 returns the latches to their initial (full line) positions, where they are again ready to automatically snap into engagement with the louver catches, one or more at a time, when the louvers are swung to closed positions. The overall length of the gang of louvers may be as desired. 45 In a vehicle installation it may be desirable to employ a gang whose overall length is such that with practically a single sweep of a hand a person may shut all or any number of the louvers.

50 The latches may if desired be positioned so

that movement of the plunger would release the louvers progressively, to automatically open less than all of the louvers. When such plunger is released, all of the latches are in place to engage the catches when the louvers are again shut.

5 The extent of opening of each louver by the spring 22 is limited by engagement of the lug 40 on the ear 19 with the nib 41 which may be formed in any suitable manner, as by depressing 10 the casing. The projection of the nib in the path of the lug is preferably slight, and the lug and/or nib is resiliently flexible to such an extent as to enable the lug, upon the application of manual force on the louver, to ride up over the nib so as 15 to be frictionally engaged therewith. The length and location of the lug and the location of the nib will determine the limit to which the spring 22 swings the louver and the angle through which the louver may be manually adjusted and frictionally held. Like pressure on the louver will 20 release it from the nib, and the resistance of the spring 22 also is readily overcome when it is desired to shut the louver.

Each louver is prevented from rattling by the 25 latches 29 when closed, by the spring 22 when partly open or ajar, and by the frictionally engaged nib and lug when the louver is further open.

In the form shown in Fig. 1, the button is disposed at the casing, where it may be pushed more conveniently by a seated passenger,—one near the driver, for example. Fig. 4 illustrates how the louvers may be dual-controlled, i. e. independently by either the driver or a passenger, for example. 30 To this end a Bowden wire or other suitable remote control connection 43 is secured to the button 38a and terminates in a knob 44 at the instrument panel 45 or other support in easy reach of the driver, for example. By pushing either the 35 knob 44 or the button 38a, the plunger 28 is moved as explained above. When the knob and button are released, the plunger is returned to its initial position by the spring 34. If desired the louvers could be controlled solely from the knob 44.

40 I am aware the reversals of parts may be resorted to, and that many other changes may be made and numerous details of construction varied through a wide range without departing from the principles of my invention, and I therefore do not purpose limiting the patent granted hereon otherwise than as necessitated by the prior art.

I claim:

1. In a ventilating apparatus comprising a motor, a fan operated thereby, a casing having an outlet for air from said fan, and means in the path of air from said fan to said outlet for altering the temperature of the air; closure means for said outlet, cooperating latch means on said casing and said closure means and constructed and arranged to automatically interlock upon shutting 55

of said closure means for holding said closure means shut, means for releasing said latch means, yieldable means for automatically moving said closure means to open position upon release of said latch means, said closure means being manually adjustable to different open positions, and means for yieldably holding said closure means in different predetermined adjustments. 5

2. An apparatus of the character described comprising a casing having a plurality of doors, a catch movable with each door, a latch for each catch and supported by said casing in position to interlock with the cooperative catch when the corresponding door is shut, means for moving said latches simultaneously to release all of the interlocked catches, said means comprising a member on which said latches are mounted and projecting from said casing so as to be operated by hand, means for opening said doors upon release of said catches, and means for returning said latches to 20 their initial positions where they will interlock with said catches when the doors are moved to closed positions.

3. An apparatus of the character described comprising a casing having a plurality of doors, 25 a catch movable with each door, a latch for each catch and supported by said casing in position to interlock with the cooperative catch when the corresponding door is shut, means for moving said latches simultaneously to release all of the interlocked catches, said means comprising a manually operable member on which said latches are mounted, means for opening said doors upon release of said catches, and means for returning said latches to their initial positions where they 30 will interlock with said catches when the doors are moved to closed positions. 35

4. A ventilating apparatus comprising a casing, a pair of doors therefor, a member provided with means projecting in the path of opening movement of a part movable with each door, said member being movable to carry said means as a unit out of said path to allow both doors to be opened simultaneously, and means for opening said doors upon movement of the first means. 40 45

5. An apparatus of the character described comprising a casing having an opening, a door therefor, a spring engaged between said casing and said door, interengageable means on said casing and door, said means being disengaged throughout a predetermined degree of movement of said door in response to the spring action and being effective upon said interengagement to overcome the spring action, said means being frictionally slidably relative to each other upon application of manual force to said door to adjustably hold said door at points beyond the zone of action of said spring. 50 55
